UNITED STATES PATENT OFFICE.

FRANK W. EDWARDS, OF CHICAGO, ILLINOIS, ASSIGNOR TO THE CHICAGO LUBRICATOR COMPANY, OF CHICAGO, ILLINOIS, A CORPORATION OF ILLINOIS.

SIGHT-FEED LUBRICATOR.

1,153,546.

Specification of Letters Patent. Patented Sept. 14, 1915.

Application filed April 16, 1915. Serial No. 21,729.

To all whom it may concern:

Be it known that I, FRANK W. EDWARDS, a citizen of the United States, residing at Chicago, in the county of Cook and State of Illinois, have invented a certain new and useful Improvement in Sight-Feed Lubricators, of which the following is a full, clear, and exact description.

This invention relates to sight-feed condensation displacement lubricators, and more particularly to such lubricators when used with down-drop feeds for supplying lubricant under steam pressure to the flanges of locomotive driving wheels.

The invention is herein illustrated and explained in connection with a four-feed lubricator, having down-drop feed tips, for use as a flange oiler, but it is to be understood that the principle of the invention and the mechanism by which it may be practically applied are applicable to other types of lubricators and to lubricators for other purposes irrespective of the number of feeds.

The invention is designed, among other things, to utilize the short, thick, stocky observation glasses of my Patents Nos. 13,474 reissued October 8, 1912, 952,515, March 22, 1910, 953,675, March 29, 1910, 1,009,290, November 21, 1911, 1,032,662, July 16, 1912, and 1,071,148, August 26, 1913, and application Serial No. 650,394, filed September 20, 1911, and also to extend the principle of protecting these glasses against exposure greater than necessary to give a clear field of vision to the user.

Other objects of the invention will appear in the explanation thereof following.

Without thereby intending to limit the invention or the scope of the claims herein, the invention may be said to consist of a lubricator having one or many one-piece sight feed bodies, pockets or packing cases of peculiar construction, in which the observation glasses are inclosed and held, and having openings or windows through which the feed of the oil may be seen, and means to connect the pockets with the oil-bowl and the parts to which the oil is to be supplied, and with the steam supply, as I will proceed now to explain and finally claim.

In the accompanying drawings illustrating the invention, in the several figures of which like parts are similarly designated, Figure 1 is a perspective view; Fig. 2 is a front elevation, partly in section; Fig. 3 is a side elevation, partly in section, and Fig. 4 is a horizontal section on line IV, of Fig. 2, showing the invention applied to a four-feed flange oiler. Fig. 5 is a side elevation of the lower steam connection. Fig. 6 is a view of a modified form of twin pockets, one pocket being in elevation and the other in section. Fig. 7 is a horizontal section on line VII of Fig. 6. Fig. 8 is a vertical section on line VIII of Fig. 6. Fig. 9 is a side elevation, and Fig. 10 is a rear end view of the steam connection used with the pockets of the form shown in Figs. 6, 7 and 8.

The oil-bowl 1, its filler plug 2, draining means 3, condenser 4, and condenser valve 5 may be of any usual or approved construction.

6 is a fitting or T adapted to be connected with a pipe 7 by which steam is received from a suitable source of supply, such as the locomotive steam boiler, a choke 8 being interposed between the fitting and the steam pipe 7. This fitting is connected with the condenser, as by a coupling 9, and with the steam circulating pipes 10. A valve 11 is interposed in the fitting between the steam or boiler connection 7 and the steam circulating pipes, for controlling the admission of steam into the condenser and to the steam circulating pipes. These steam circulating pipes enter fittings or elbows 12 which are provided with outlets 13, and these outlets are connected with the sight feed pockets, bodies, or packing cases 14 so as to deliver steam to the discharge ends of these pockets not only to carry the oil or lubricant to its destination, but also, in the case of a flange oiler, to forcibly project the oil against the wheel flanges. In order to avoid repetition and for the sake of uniformity and conciseness the parts 14 are hereinafter referred to as pockets.

As shown in Fig. 2, the discharge or delivery pipe 15 is connected with the pocket by a coupling 16 in which is interposed a

suitable choke plug 17, and the pipe 15, as indicated at the right-hand side of Fig. 3, leads down to the flange-nozzle or delivery device 18 by means of which the lubricant 5 is delivered to the wheel flange, as above mentioned. Only one of these nozzles is shown, see Fig. 3, but it is to be understood that one is used for each pocket, and, obviously, any other delivery device may be 10 used to suit the purposes for which the lubricator is employed. The steam circulating pipe elbow 12 may have an extension 19 to receive a suitable bolt 20 for rigidly connecting the elbow and pocket with the 15 oil-bowl. The pockets 14 are bottle-shaped, and each has an open bottom and top, and the bottom is provided with an internal screwthread 21 or other suitable means to receive a screw-plug 22 or other appropriate 20 closure, and the top or neck of the bottle is likewise screwthreaded to receive a hub 23 which carries the oil feed valve 24. Inside and below the neck is a web 25 having a screwthreaded hole to receive the down-drop 25 feed tip 26. Below this web is a recess 27, and below this recess is a shoulder 28 whence the diameter of the pocket extends to the bottom substantially uniformly, excepting that about the middle of the body are 30 windows or openings 29 slightly offset from the inside diameter. These windows are arranged around the pocket so as to admit light into the pocket from all directions. The observation glass 30 may be of any one 35 of the various types illustrated in the patents above referred to, or any other approved style, preferably short, thick and stocky, and it is inserted longitudinally in the pocket with the washer 31 and gasket 40 32 arranged adjacent to its upper shoulder and between such shoulder and the shoulder 28 in the body. 33 is a gasket and 34 a washer arranged on the lower shoulder of the glass and engaged by the packing stem 45 head or cup 35 which is provided with the rim or ledge 36 to receive and engage the washer and gasket. This cup 35 is mounted upon or is made as a part of the packing stem 37 which is adjustably supported in 50 the screw-plug 22 and provided with a squared end 38 or other means by which it may be turned within this screw-plug. The cup or head 35 is provided with any number of openings 39 for the escape of the oil 55 into the bottom of the pocket, whence, as previously described, it is distributed to the points of application. As will be seen, the pockets may be made in pairs or as twins, and this is one of the features of novelty 60 herein. As thus made, the pockets are connected in pairs by a transverse pipe 40, and this pipe 40 is provided with a nipple or arm 41 arranged about midway between the pockets. By means of the extension coupling

42, the pockets are connected with the oil-bowl in such way that the displaced oil may overflow through the extension coupling 42 and nipple 41 into the down-drop feed tip 26. The pairs of pockets are connected also at or near their bottoms, as by the steam 65 pipes or tubes 43, which open into both of the pockets of the pairs and are connected with the steam circulating pipe elbow. When four points, or places, or objects, are 70 to be lubricated, the pockets are located in 75 pairs on opposite sides of the oil-bowl, as indicated more particularly in Figs. 1, 3 and 4.

Referring to Figs. 6 to 10, it is noted that in addition to the features above described, 80 the two pockets comprising each pair may be connected by a hollow vertically arranged web 44, and this may be used to receive steam in order to keep the pockets reasonably warm so as to insure the flow of the 85 lubricant. Also, as shown in these views, the connection 45 with the steam circulating pipe elbow may be made considerably above the bottom, practically about midway 90 between the top and bottom of the body, and in this case the steam circulating pipe elbow 46 will be modified accordingly, as shown in Figs. 9 and 10. Introducing the steam as just described provides for the gradual 95 heating of the glass within the sight feed body, and in a more even way than when the steam is admitted directly at the bottom of the glass as first described. Otherwise than as stated, the modified form of pocket last described is essentially the same as that first 100 described.

As distinguishing from the one-piece packing case of my patents referred to, it is to be noted that the bottle-shaped pocket of the present invention has its upper end 105 shaped to receive the upper packing of the glass and that the pressure to compress the gaskets at top and bottom of the glass is applied from below through the medium of the adjustable packing cup. 110

Assuming that the invention is applied to a four-feed flange-oiler, the device is operated as follows: First open the steam valve 111 fully, so as to permit steam to pass from the boiler or other source of supply directly 115 into the flange oiler fitting or connection 6, and thence to the circulating pipes and to the condenser. As the steam passes down through the circulating pipes, it flows directly into the steam circulating pipe elbows 120 and thence into the cross-connecting tube. As the steam passes into this connecting tube, it is distributed to both of the oil delivery pipe connections into which it passes through the choke valves and thence flows 125 down to and through the flange nozzles to the place of use. The condenser valve 5 is then opened, and the feed valve regulated,

the water of condensation passing from the condenser to the bottom of the oil-bowl and displacing the oil in the usual way, whence it flows to the feed tips and thence escapes 5 drop by drop into the observation tubes or glasses. As the oil reaches the bottom of the sight feed glasses, it comes into contact with the bottom of the cup or head in the packing stem and thence escapes through the 10 holes 39. As soon as the oil passes through these holes it comes directly into line with the steam flow and is carried by and with the steam in both directions through the chokes 17 into the oil delivery pipes and 15 thence out through the flange nozzles.

The operation of the modified form of the pockets or bodies is substantially the same as that just described.

By the construction described, a very servable lubricator is produced and considerable economy in fittings, as well as in parts to be repaired or replaced, is effected. The connection of the pockets with the oil-bowl at the top by the extension coupling and the 25 use of the steam-pipe elbows fixed to the oil-bowl makes a rigid and compact construction, which also presents readily accessible means for assembling, dismemberment and repairs.

30 Of course, it is understood that the invention is applicable to a single feed lubricator or to a multiple feed lubricator; and the use of the invention, obviously, is not restricted to flange oilers.

35 What I claim is:—

1. A sight feed lubricator, having a one-piece sight feed pocket provided with a packing-receiving shoulder at its upper portion, and adapted to contain a tubular observation glass, and a pressure applying and glass supporting device arranged in the bottom of the pocket and engaging the observation glass adjustably.

40 2. A sight feed lubricator, having twin sight feed pockets made in a single piece, and adapted to contain tubular observation glasses, and provided in their bottoms with adjustable glass-supporting cups.

3. A sight feed lubricator, having a one-piece bottle-shaped pocket or body provided with windows, and having a glass-receiving cavity and a glass supporting and tightening means arranged in the bottom of the pocket.

45 4. A sight feed lubricator, having a one-piece sight feed pocket provided with an oil inlet at its upper end, a down-drop feed tip, an observation glass, an adjustable glass support, windows to expose the glass, a bottom oil outlet, and a steam connection communicating with such outlet.

50 5. In a sight feed lubricator, the combination with the oil-bowl, and steam supply, of a series of one-piece sight feed pockets,

and a steam connection for connecting the 65 pockets with the steam supply and fastening them to the oil-bowl.

6. In a sight feed lubricator, twin sight feed pockets made in a single piece, open at top and bottom, having circumferential windows, and oil and steam connections. 70

7. In a sight feed lubricator, twin sight feed pockets made in a single piece, open at top and bottom, having circumferential windows, a steam heating element, and oil and 75 steam connections.

8. In a sight feed lubricator, twin sight feed pockets made in a single piece, open at top and bottom, having circumferential windows, an oil connection at the top, a steam 80 connection below, and oil and steam exits at the bottom.

9. A sight feed lubricator, having an observation glass, and a one-piece pocket, provided with a shoulder in its upper portion 85 against which the upper part of the glass is pressed, combined with a glass supporting cup arranged in the bottom of the pocket beneath the glass, an adjusting stem for such cup, and a hub for closing the bottom 90 of the pocket and receiving and sustaining the adjusting stem.

10. A sight feed lubricator, having twin sight feed pockets made in a single piece, and adapted to contain tubular observation 95 glasses, combined with an oil-bowl, an oil connection at the top, and an extension feed arm applied to such connection and adapted to engage the oil-bowl.

11. A sight feed lubricator, having twin 100 sight feed pockets, made in a single piece, and adapted to contain tubular observation glasses, combined with an oil-bowl, an oil passage at the top, an extension arm for connecting such passage with the oil-bowl, a 105 steam supply, a steam passage at the bottom, an elbow for connecting such passage with the steam supply, and outlets for the oil and steam.

12. The combination with an oil-bowl, a 110 condenser, steam circulating pipes, means to connect such pipes with a steam supply, a valve for controlling the admission of steam to such pipes, a pair of twin sight feeds, an oil passage and a steam passage connecting 115 said sight feeds, an oil connection between said oil passage and the oil-bowl, a steam connection between said steam passage and said steam circulating pipes, and combined oil and steam outlets from said sight feeds. 120

13. A four-feed flange oiler, comprising an oil-bowl, a condenser, steam circulating pipes, means to connect such pipes with a steam supply, a valve for controlling the admission of steam to such pipes, pairs of twin 125 sight feeds, each twin having an oil connection at top and a steam connection below, means to connect the oil connections with

the oil-bowl, means to connect the steam connections with the steam circulating pipes, independent combined oil and steam outlets, one for each sight feed, and delivery means 5 leading from said outlets to the several flanges to be oiled.

In testimony whereof I have hereunto set my hand this 13th day of April A. D. 1915.

FRANK W. EDWARDS.
